ADHESIVE TAPE APPLIER

Louis H. Morin, New York, N. Y., assignor to Industrial Tape Corporation, a corporation of New Jersey

Application June 26, 1945, Serial No. 601,691

12 Claims. (Cl. 216—33)

1
This invention relates to a tape dispensing and applying device of the character wherein a strip of pressure-sensitive adhesive tape is applied to the corner of a box or package to effect a seal.

Such corner sealing devices consist, usually, of a supporting platform for the package or box to be sealed and an applying means in the form of a roller presented by an arm which extends through the package-supporting platform together with means for positioning a piece of tape in advance of the applying roller. The applying roller, as the package is advanced against it, applies the tape first to one face of the box and then to the adjacent face of the box as the roller is depressed to permit the box to override it.

In the corner sealing devices of the prior art, a severed length of tape is presented in position for application to the box to be sealed and, as the box is advanced against the tape to complete the sealing operation, other mechanism operates to present a second severed length of tape in operative position for the next sealing operation. Such machines are quite complicated and expensive to manufacture.

The improved machine is of vastly simpler construction. There is no complicated mechanism for causing the adhesive tape to be advanced through the machine to the place where it is presented in operative position for the sealing operation. On the contrary, the tape is pulled through the machine by the package which is being sealed. The tape is severed after it has been applied to the box, the severing and applying means functioning in such a way that the new end of the tape, i. e., the forward end of the tape remaining in the machine is located in a position ready for the next sealing operation. Many other advantages of the improved machine will be apparent as the description of the invention proceeds.

Referring to the drawings,

Fig. 1 is a plan view of a tape dispensing and applying device equipped with the present improvements;

Fig. 2 is a vertical longitudinal section on line 2—2 of Fig. 1;

Fig. 3 is a vertical transverse section on line 3—3 of Fig. 2;

Fig. 4 is a vertical transverse section on line 4—4 of Fig. 2;

Fig. 5 is an enlarged end elevation of the tape-applying roller;

Fig. 6 is a vertical section on line 6—6 of Fig. 5, showing the tape-severing means in its operative or tape-severing position;

2
Fig. 7 is a fragmentary view similar to Fig. 6, but showing the tape-severing means in its retracted or inoperative position;

Fig. 8 is a partial vertical longitudinal section 5 through the machine showing the parts after the box has been partially sealed and just prior to the time the used tape is severed from the roll;

Fig. 9 is an enlarged fragmentary view, partly in section, of the tape-applying roller in a position just prior to the operation of the tape-severing means.

Fig. 10 is a view similar to Fig. 9, showing the parts just after the completion of the tape-severing operation, but prior to the return of the 15 tape-applying roller to its normal position;

Fig. 11 is a side elevation of a different modification of a tape dispensing and applying device equipped with the present improvements; and

Fig. 12 is a plan view of the device shown in Fig. 11.

The improved tape dispensing and applying device comprises a housing 10 at one end of the machine for the operating mechanism and a pair of vertical parallel standards 11 at the opposite end of the machine to support a roll 12 of pressure-sensitive adhesive tape (Figs. 1 and 2). The standards rise from a base 13 and are spaced apart sufficiently to accommodate a drum 14 whose width is sufficient to accommodate the size of tape to be used in the sealing operation. The standards 11 are formed in their inner faces with a pair of opposed inclined slots 15 open at the top to accommodate the ends of a hub 16 with which the tape supporting drum 14 is equipped at the center, and closed at the bottom to support the sub and consequently the drum so that the roll of tape is free to rotate as the tape is unwound during the tape dispensing operation.

The housing 10 at the end adjacent the supply roll, is closed by a vertical wall 17 rising from the base 13, although this wall is split vertically at the center so as not to interfere with the tape as it threads through the machine.

The remainder of the housing is defined by side walls 18 and an end wall 19 rising from the base 13 to form the lower half of the housing and a top plate 20 having side walls 21 and an end wall 22 depending from the top plate to form the

50 upper half of the housing in conjunction with the upper half of the wall 17 (Figs. 2, 3 and 4). The top plate 20, the side and end walls 21 and 22 constitute a cover plate which is pivotally mounted at the ends of a transverse shaft 23 supported in a bracket 24 fixed on the base 13. Its

normal or closed position is determined by a pair of lugs 25 protruding inwardly from the opposite lower side walls of the housing and against which the opposite side walls 21 of the cover plate bank at their lower edges. The cover plate is held in its closed position by a spring detent 26 which engages beneath the bottom edge of the end wall 22 to prevent rotation of the cover plate about its supporting shaft. The spring detent may be withdrawn normally from beneath the edge of the cover plate to permit the latter to swing to the dotted line position shown in Fig. 2 when access to the mechanism within the housing is desired, as, for instance, when it is necessary to thread a new roll of tape through the machine.

As the tape leaves the supply roll 12, it passes over and with its adhesive face in contact with a roller 27 and then beneath a tape-applying roller 28 mounted for rotation about its own axis at the end of the arm 29 of a lever 30. The arm 29 extends through an aperture 31 in the cover plate so that the roller 28, in its normal position, is located somewhat above the top surface thereof. The lever 30 has a hub portion 33 drilled to accommodate the transverse shaft 23 on which it is rotatably mounted. The lever 30 also has a second arm 34 extending downwardly from the hub portion and which banks at its lower end against a stop 35 presented by the supporting bracket. A torsion spring 36, encircling the shaft 23, and reacting between a fixed buttress 37 on said shaft and the lever 30, urges the lever arm 34 against the stop 35, thereby locating the lever and consequently the applying roller in their normal positions (Figs. 2 and 3).

The tape, near its free end, is held adjacent the applying roller, with the adhesive surface out, by a small finger 32 mounted on the lever arm 29. The mounting of the finger 32 is such that the tape may be threaded between the applying roller and the finger merely by slipping the tape in edgewise. As previously stated, the applying roller 28 is mounted for rotation about its own axis. For this purpose, it is fixed at one end of a spindle 38 journaled near the end of the arm 29 which is enlarged to give adequate bearing surface (Figs. 3 and 6). A concentric flange 39 at the opposite end of the spindle bears against the enlarged portion of the arm 29 to hold the spindle against endwise movement. The applying roller 28 has a normal position relative to its supporting arm (Figs. 2 and 3). This position is determined by a spring 40 anchored, at one end, to a pin 41 protruding from the flange 39 in a position parallel with but eccentric to the axis of the applying roller and, at its opposite end, in the arm 29.

The construction of the applying roller 28 is best illustrated in Figs. 5, 6 and 7. It comprises a hub portion 42 terminating at one end in a flange 43 and provided at its opposite end with a plate 44 similar in size to the flange and which is slotted as at 45 to receive a pair of fingers 46 protruding endwise from the hub portion to lock the plate and the hub portion against relative rotation. The plate, and consequently the applying roller, are suitably held on the spindle 38 by a screw threaded endwise into the latter. The flange 43 and plate 44 hold between them a rubber tire 45 to present increased frictional engagement with the tape.

A tape-severing knife 46, consisting of a blade with serrated outer edge, is mounted in a slot

presented by a U-shaped member 47 extending lengthwise of the applying roller and fixed in the flanges thereof (Figs. 6, 7 and 8). The blade is arranged for limited parallel movement in a radial direction and, to this end, is provided, near its opposite ends, with slots 48 disposed at angles of 45° with the axis of the roller. The flange 43 and plate 44 are notched as at 49, to permit the insertion of pins 50 which pass through the slots in the knife perpendicularly to the latter and which, in conjunction with the slots serve to limit the edgewise radial movement of the knife blade. In the normal position of the knife blade, its serrated edge is located below the peripheral surface of the roller, in which position it is held by a leaf spring 51 fastened to the outer flange of the roller and so disposed that its free end, resiliently engages the knife blade at its adjacent end.

In operation, the box A to be sealed is placed upon the platform presented at the top of the cover plate 20 with one of the surfaces defining the corner to be sealed, facing the adhesive side of the tape which protrudes between the applying roller 28 and the finger 32 (Figs. 2, 8, 9 and 10). The box is then moved as rapidly as desired against the tape and the applying roller and along the platform until it is arrested by a cushioning stop 52 fixed at the opposite end thereof. During the initial movement of the box, the tape is pressed by the applying roller firmly against the face of the box initially presented to the tape. As the movement of the box continues, the applying roller is forced downwardly through the aperture 31 in the cover plate allowing the box to ride over it but, since this action is against the tension of the spring 36 acting on the roller-supporting lever 29, the roller at all times presses the tape firmly in contact with the box. This action continues after the used portion of tape has been severed from the remainder of the roll in order that the severed end of the used portion is likewise pressed in firm contact with the box.

The tape severing operation will now be described. When the applying roller 28 is in its normal position as determined by the tension spring 40, the cutting knife 46 is located a substantial distance around the periphery of the roller from the point at which the latter is initially engaged by the box (Fig. 2). However, as the applying roller is rotated against the tension of the small spring 40, by the movement of the box and by the pull of the tape in contact therewith, it arrives at the position shown in Fig. 9, just prior to the end of the tape applying stroke. Continued rotation of the roller beyond this point causes an end portion 53 of the knife 46, which protrudes for a short distance beyond the flange 43 of the applying roller, to engage a roller 54 mounted on a pin secured at the end of the lever arm 29 (Figs. 6, 7, 9 and 10). As the knife engages the roller 54 it is cammed endwise against the action of the leaf spring 51 and also edgewise outwardly, causing its serrated edge to protrude beyond the surface of the applying roller and perforate the tape.

Simultaneously with the arrival of the knife in the tape cutting position, the eccentric pin 41 on the roller supporting spindle banks against a stop 55 presented by the supporting bracket 24. Further rotation of the applying roller is thereby halted and, since its downward movement has also been arrested at this time by the engagement of a stop 56 on its supporting lever with the underlying bracket, the knife is firmly positioned,

enabling the perforated tape to be completely severed by the continued movement of the box as it approaches the banking stop 52.

Upon completion of the sealing operation, the box is removed from the platform thereby freeing the applying roller which is returned to its normal position by the respective springs acting on the lever arm 29 and the eccentric pin 41, it being understood that the applying roller will be free to rotate to its normal position as soon as the eccentric pin moves away from the stop. In turning the applying roller to its normal position, the spring 40 pulls the knife blade 46 past the roller 54. As this occurs, the leaf spring 51 restores the knife blade to normal position with its serrated edge below the surface of the applying roller.

Allusion is now made to the construction and function of the roller 27 which is next adjacent the tape supply roll and over which the tape travels as it threads through the machine. It will be observed that there is a substantial portion of tape extending beyond the retaining finger 32 and which is initially applied to the box when the latter is brought into engagement with the tape and pressed against the applying roller. Substantially the same amount of tape extends beyond the finger 32 after the used portion has been severed. It is desirable that some means be provided to prevent the back drag of the tape from changing this condition as the applying roller is restored to its normal position from that shown in Fig. 10. The roller 27 and its associated mechanism serve this purpose. The roller 27 is mounted for rotation at the upper end of a lever 57 which is pivotally mounted adjacent its center on the supporting brackets 24 (Fig. 2). This lever, at its lower end, is connected by means of a link 58 to the depending arm 34 of the lever 30 which carries the applying roller. There is also mounted on the lever 57 a pivotally mounted pawl 59, spring-pressed into engagement with a toothed ratchet wheel 60 formed integrally with the roller 27. The arrangement is such that as the applying roller moves downwardly during a corner sealing operation, the lever 57, through its connection with the lever 30, is rocked from the position shown in Fig. 2 to the position shown in Fig. 8. This action, however, has no effect upon the feeding of the tape since the pawl and ratchet arrangement 59, 60, is such that, as the roller 27 moves toward the supply roll of tape, it turns idly with the pawl merely slipping over the teeth of the ratchet wheel. However, as the applying roller is restored to its normal position after a tape sealing operation, the lever 57 is likewise restored. During this movement of the lever 57 the roller 27 is locked by the pawl 59 against its tendency to rotate under the back drag of the tape. The result is that a further portion of the tape is pulled off the supply roll sufficient in amount to counteract any tendency for the tape to become unthreaded from between the finger and the applying roller during the return of the latter to normal position. The roll 27 is formed with a series of annular ribs to provide a sufficient amount of adhesion between it and the tacky side of the tape to prevent relative slipping without, however, interfering too much with the feed of the tape during a corner sealing operation.

It will thus be seen that the improved machine is one requiring a minimum number of parts and capable, because of its simplicity, of very efficient operation.

The modification of the invention shown in 75

Figs. 11 and 12 is, in most respects, substantially the same in principle as that previously described. Thus, it is provided with a supply roll of tape 70 from which the tape is led over a roller 71 with the adhesive side in contact therewith, and which is arranged to idle in the direction of tape feed. After it leaves the roller 71, the tape is threaded between an applying roller 72 and a finger 73 to present the end of the tape with its adhesive side outwardly in a position to be engaged by the box to be sealed when the box is pushed against the tape and the applying roller.

In this instance, however, the box-arresting stop 74 is arranged on a vertical wall adjacent the platform which supports the box during the corner sealing operation.

The applying roller is rotatably mounted at the end of one arm of a lever 75 pivotally mounted adjacent its center and which is urged by spring tension acting upon a second arm, to hold the latter against a stop 76 which locates the applying roller in a position to be engaged by the box to be sealed. The applying roller 72 is also equipped with a knife 77 resiliently maintained in its normal position by a spring 78 secured at one end to an eccentric pin 79 carried by the roller and which is anchored at its opposite end in the lever 75.

The method of applying the tape to the box is 30 the same as in the modification previously described, namely, the box is pushed against the applying roller, which causes the latter to be moved downwardly and simultaneously rotated as the tape is fed and applied to the box during 35 the corner sealing operation. The used portion of the tape is severed from the remainder of the roll after it has been applied to the box.

As the roller is restored to its normal position after a corner sealing operation, the tape is held 40 against back-pull, which might tend to unthread it from between the applying roller and the supporting finger, by the roller 71 which is equipped with a pawl and ratchet mechanism 80, serving to prevent reverse rotation of the roller.

The essential difference between this modification and that previously described is that the roller 71 is rotatably mounted on a fixed pin and consequently does not pull any extra tape off the roll as the parts are restored to their normal positions. Despite this, however, there is no unthreading of the tape from between the roller 72 and the finger 73. It will be noted that when the pin 79 on the roller 72 banks against a stop 81 the arm 75, on which the roller is mounted, simultaneously banks against a limiting stop 82. Further movement of the roller 72 is thereby prevented while continued movement of the box in the direction of the stop 74 acts to sever the tape that has been applied to the box at the position where it was perforated by the knife 77. In the arrested position of the roller 72, the knife 77 has rotated somewhat further than in the modification previously described, and the amount of the tape that extends around the roller 72 up to the 65 knife is such that even though the tape is pulled backwards with reference to the finger 73 as the roller 72 is restored to its normal position, there nevertheless remains a sufficient section of tape extending upwardly beyond the finger 73 to be engaged by a box in the next sealing operation.

The invention has been described by way of example only and many other modifications thereof are included within its spirit. The invention, therefore, is to be limited only by the prior art and the scope of the appended claims.

What I claim is:

1. Adhesive strip applying apparatus comprising a roller arranged resiliently to press a strip of adhesive material into adhesive engagement with an article upon movement of the article in one direction, means including said roller for holding the leading end of the strip in position to be engaged by the article upon the inauguration of its movement, and means carried by said roller operable to sever a portion of the strip after it has been applied to the article.

2. Adhesive strip applying apparatus comprising a roller arranged resiliently to press a strip of adhesive material into adhesive engagement with an article upon movement of the article in one direction, means including said roller for holding the leading end of the strip in position to be engaged by the article upon the inauguration of its movement, and a blade carried by said roller movable from an inoperative to an operative position to sever a portion of the strip after it has been applied to the article.

3. Adhesive strip applying apparatus comprising an article supporting platform, a rocker arm, a roller mounted thereon for rotation about its own axis and movable from a normal position to apply a strip of adhesive material to an article upon movement of the latter in one direction along the platform and returnable into normal position after the strip has been applied, spring means acting on the rocker arm for causing the roller to press the strip of adhesive material into engagement with the article, means including said roller for holding the leading end of the strip in position to be engaged by the article upon the inauguration of its movement, and means for severing the portion of the strip that has been applied to the article.

4. Adhesive strip applying apparatus comprising an article supporting platform, a rocker arm, a roller mounted thereon for rotation about its own axis and movable from a normal position to apply a strip of adhesive material to an article upon movement of the latter in one direction along the platform and returnable into normal position after the strip has been applied, spring means acting on the rocker arm for causing the roller to press the strip of adhesive material into engagement with the article, means including said roller for holding the leading end of the strip in position to be engaged by the article upon the inauguration of its movement, and a blade carried by said roller, said blade being movable from an inoperative to an operative position to sever the portion of the strip that has been applied to the article.

5. Adhesive strip applying apparatus comprising an article supporting platform, a rocker arm, a roller mounted thereon for rotation about its own axis and movable from a normal position to apply a strip of adhesive material to an article upon movement of the latter in one direction along the platform and returnable into normal position after the strip has been applied, spring means acting on the rocker arm for causing the roller to press the strip of adhesive material into engagement with the article, means including said roller for holding the leading end of the strip in position to be engaged by the article upon the inauguration of its movement, means for locating the roller in a normal position relative to its supporting rocker arm, and means operating after a predetermined rotational movement of the roller from its normal position to

sever the portion of the strip that has been applied to the article.

6. Adhesive strip applying apparatus comprising an article supporting platform, a rocker arm, a roller mounted thereon for rotation about its own axis and movable from a normal position to apply a strip of adhesive material to an article upon movement of the latter in one direction along the platform and returnable into normal position after the strip has been applied, spring means acting on the rocker arm for causing the roller to press the strip of adhesive material into engagement with the article, means including said roller for holding the leading end of the strip in position to be engaged by the article upon the inauguration of its movement, means for locating the roller in a normal position relative to its supporting rocker arm, and a blade carried by said roller movable from an inoperative to an operative position after a predetermined rotational movement of the roller for severing the portion of the strip that has been applied to the article.

7. Adhesive strip applying apparatus comprising an article supporting platform, a rocker arm, a roller mounted thereon for rotation about its own axis and movable from a normal position to apply a strip of adhesive material to an article upon movement of the latter in one direction along the platform and returnable into normal position after the strip has been applied, spring means acting on the rocker arm for causing the roller to press the strip of adhesive material into engagement with the article, means including said roller for holding the leading end of the strip in position to be engaged by the article upon the inauguration of its movement, means for locating the roller in a normal position relative to its supporting rocker arm, a blade carried by said roller movable from an inoperative to an operative position after a predetermined rotational movement of the roller for severing the portion of the strip that has been applied to the article, and means for restoring the roller to its normal position relative to its supporting rocker arm.

8. Adhesive strip applying apparatus comprising an article supporting platform, a rocker arm, a roller mounted thereon for rotation about its own axis and movable from a normal position to apply a strip of adhesive material to an article upon movement of the latter in one direction along the platform and returnable into normal position after the strip has been applied, spring means acting on the rocker arm for causing the roller to press the strip of adhesive material into engagement with the article, means including said roller for holding the leading end of the strip in position to be engaged by the article upon the inauguration of its movement, means for locating the roller in a normal position relative to its supporting rocker arm, a blade carried by said roller, means operable after a predetermined rotational movement of the roller from a normal position to move the blade from an inoperative to an operative position to sever the portion of the strip that has been applied to the article, and independent means for restoring the blade and the roller to their respective normal positions.

9. Adhesive strip applying apparatus comprising a device movable from a normal position to apply a strip of adhesive material to an article upon movement of the latter in one direction and returnable into normal position after the strip has been applied, means including said

device for holding the leading end of the strip in position to be engaged by the article upon the inauguration of its movement, means for severing the portion of the strip applied to the article, and means for preventing the withdrawal of the strip from its article engaging position as the applying device is restored to its normal position ready for the next strip applying operation.

10. Adhesive strip applying apparatus comprising a device movable from a normal position to apply a strip of adhesive material to an article upon movement of the latter in one direction and returnable to normal position after the strip has been applied, means including said device for holding the leading end of the strip in position to be engaged by the article upon the inauguration of its movement, means for severing the portion of the strip that is applied to the article, means comprising a roller having adhesive contact with the strip and arranged to idle as the strip is applied to the article, and means for locking the roller to prevent withdrawal of the strip from its article engaging position as the applying means returns to normal position.

11. Adhesive strip applying apparatus comprising a device movable from a normal position to apply a strip of adhesive material to an article upon movement of the latter in one direction and returnable to normal position after the strip has been applied, means including the applying device for holding the leading end of the strip in position to be engaged by the article upon the inauguration of its movement, means for severing the portion of the strip that is applied to the

article, means comprising a roller having adhesive contact with the strip and arranged to rotate idly in one direction as the strip is applied to the article, means actuated by the movement of the strip applying device for displacing the roller in a direction opposite to the advance movement of the strip, and means for locking the roller against rotation in the reverse direction to prevent withdrawal of the tape from its article engaging position as the applying device returns to normal position.

15. Adhesive strip applying apparatus comprising a presser device movable from one position to a second position to apply an adhesive strip of material to an article and returnable to its initial position after the strip has been applied, means for holding the leading end of the strip in position to be engaged by the article in the initial position of the presser device and means 20 carried by the presser device and operable when the presser device is in the second mentioned position to sever that portion of the strip that has been applied to the article.
